UNITED STATES PATENT OFFICE.

WILLIAM M. VENABLE, OF PITTSBURGH, PENNSYLVANIA, ASSIGNOR TO BLAW-KNOX COMPANY, A CORPORATION OF NEW JERSEY.

EXCAVATING-BUCKET.

1,350,124.

Specification of Letters Patent. Patented Aug. 17, 1920.

Application filed January 22, 1920. Serial No. 353,175.

To all whom it may concern:

Be it known that I, WILLIAM M. VENABLE, a citizen of the United States, residing at Pittsburgh, in the county of Allegheny and 5 State of Pennsylvania, have invented certain new and useful Improvements in Excavating-Buckets, of which the following is a specification.

This invention relates in general to excavating or clam shell buckets and in particular to certain improvements by means of which the material being operated upon is more readily cut and prepared for removal by the bucket. It has for its primary object 10 the provision of an improved construction wherein the work of cutting into and removing the material being excavated is facilitated and made more rapid and wherein each closure of the bucket in gathering material loosens and prepares the body of the 15 remaining material for the next gathering operation. It is a further object of this invention to utilize the means whereby the foregoing results are obtained to increase 20 the effective width of the bucket in such a way as to prevent it from tipping over when it is set down on uneven ground and the holding line slacked off. The manner in 25 which all of the foregoing is accomplished 30 will more clearly appear below in connection with the description of the accompanying drawings which illustrate my invention in its preferred form and wherein:

Figure 1 is a plan view of an excavating 35 or clam shell bucket in open position showing my improvements embodied therein; Fig. 2 is a side elevation of the bucket in its open position; Fig. 3 is an end elevation of the bucket in its open position; and Fig. 4 40 is a side elevation of the bucket in its closed position.

The bucket I have illustrated comprises the two jaws or scoops 1 and 2, provided with suitable hinge elements 3 and 4 respectively 45 by means of which they are pivoted together upon the rod 5. The upper portion of the bucket mechanism is not shown inasmuch as its construction is immaterial in so far as the present invention is concerned which, it will 50 be understood, is equally applicable to any type of excavating or clam shell bucket.

At each side and to the rear of each scoop I have provided a cutting member or plow-share 6 which may be secured to the bucket 55 in any preferred manner. In the present

instance, I have shown for this purpose, a continuous band or strip of metal 7, one for each scoop, which is bent in at the sides of the scoop and secured thereto at the points I have marked 8, and curved around the 60 plowshares 6, as shown, and then run straight across the back of the scoop where it is braced by means of the brackets 9. The plowshares are preferably so attached that when the bucket is in open position they are 65 disposed with their points downward, but not projecting below the cutting edges 10 of the scoop. When the bucket is in closed position, the points of the plowshares on each side of the bucket will come almost together, 70 as shown in Fig. 4.

If the plowshares be attached in the manner I have shown by means of the band of metal 7, I prefer to space this band away from the back of the scoop and to so dispose 75 it that it will act as a supplementary cutting member or edge which will dig into the material with a spade-like action very similar to that effected by the cutting edges 10 of the bucket scoop, the material of course passing between the band and the back of the scoop and over its upper edge, but not into the bucket. This action takes place during 80 every closing movement of the bucket and it will be apparent aids greatly in loosening 85 and preparing the body of material remaining for the next gathering operation.

With respect to the plowshares, it will be seen that they enter the material substantially vertically at a point considerably far 90 further out from the center of the bucket than the corners of the scoops, and that as the bucket is closed they shovel into the material turning a furrow over toward the center. After the bucket is closed, it is then 95 raised and the material which is above the plowshares slides off toward the center of the position occupied by the bucket.

By placing these cutting members at some distance to the sides and to the rear of the 100 scoops they function, it will be seen, to provide two very important advantages. They loosen the material outside of the area covered by the open scoop and throw it toward the middle, thus digging a hole larger than 105 the size of the scoop itself, both in width and in length. Furthermore the possibility of the bucket's tipping over is greatly reduced, should it happen to be set down where the material was very uneven. 110

This device is especially useful in connection with the digging of a deep pit especially where the work is being carried on in sand or gravel in the natural bed, it being possible to dig to almost any depth in such material, which keeps sloughing in from the side toward the center.

This device is also very effective in digging into material which would ordinarily be too hard to permit the scoops to settle into it when the bucket is set down and where this hard material is very uneven, as before pointed out, the tendency for the bucket to tip is greatly reduced. This last advantage is of especial importance when the device is used on a bucket of the single line type which, of course, does not have the support of a separate holding line when it is set down.

A further advantage incident to the invention is the reduced strain and wear imposed upon the lips of the bucket due to the fact that the cutting members loosen the material preliminarily to the collecting or gathering operation of the jaws. The apparatus is thus rendered more durable. The particular construction I have shown is exceedingly strong and simple, readily made and easily attached to any bucket. The plowshares may be made in separate pieces so that they may be renewed when broken or worn out. Furthermore the apparatus may be made readily detachable so that it may be taken off when not needed.

It will, of course, be understood that the disposition of and the means for attaching the cutting elements as shown in this application is not essential in the exact form illustrated. Any arrangement of the cutting elements which loosens the material in an area greater than that covered by the open scoop would accomplish the purpose sought, but the arrangement I have shown is the preferred one.

I claim:

1. The combination with a clam shell bucket having opposing jaws, of cutting members secured to the jaws but spaced away therefrom.
2. The combination with a clam shell bucket having opposing jaws, of a pair of plowshares secured to the jaws in such man-

ner as to bring their points above the level of the cutting edges of the jaws when the bucket is open and to bring their points substantially together when the bucket is closed.

3. In a bucket having a pair of scoops hinged together for opening and closing movement, the combination of cutting members and means for attaching them in a spaced relation to the bucket so that upon closure of the bucket they will cut through the adjacent material.

4. The combination with a bucket having a pair of scoops hinged together for opening and closing movement, of a cutting member attached thereto so as to cut a furrow in the adjacent material during closing movement and to throw the material so cut toward the bucket.

5. The combination with a bucket having a pair of scoops hinged together for opening and closing movement, of a cutting member attached thereto so as to cut into and loosen the adjacent material not being directly operated on by the bucket during closing movement.

6. The combination with a bucket having a pair of scoops hinged together for opening and closing movement, of a cutting member attached to the back of a scoop and spaced away therefrom.

7. The combination with a bucket having a pair of scoops hinged together for opening and closing movement, of a cutting member at each side of the bucket, and a back band across an end of the bucket but spaced away therefrom, said back band coöperating with the cutting members at the sides to loosen the material adjacent the bucket during movement of the scoops.

8. The combination with a bucket having a pair of scoops hinged together for opening and closing movement, of a pair of plowshares attached to each side of the bucket so disposed as to bring the points of a pair approximately together when the bucket is in closed position and to bring the points above the cutting edges of the scoops when the bucket is in open position.

In testimony whereof, I have hereunto signed my name.

WILLIAM M. VENABLE.
